UNITED STATES PATENT OFFICE.

WILLIAM B. TUNSTALL, OF WORCESTER, MASSACHUSETTS.

AUTOMATIC MECHANISM FOR PLAYER PIANOS.

Application filed January 28, 1921. Serial No. 440,589.

To all whom it may concern:

Be it known that I, WILLIAM B. TUNSTALL, a citizen of the United States, residing at Worcester, in the county of Worcester and State of Massachusetts, have invented new and useful Improvements in Automatic Mechanism for Player Pianos, of which the following is a specification.

The invention is embodied in certain improvements hereinafter described and claimed, in pneumatically operated automatic mechanism for musical instruments, having for their objects improved control by the operator of the dynamics of the instrument, a more sensitive and quickly operating system requiring a minimum of future adjustments while still allowing of convenient accessibility to internal and obstructed parts when said adjustments may be necessary.

Of the accompanying drawings forming a part of this specification,—

Figure 1 is an end elevation, showing the exterior of a structure embodying the invention.

Figure 2 is a fragmentary view, showing in vertical section portions of the structure shown by Figure 1.

Figure 3 is a view similar to Figure 2, illustrating a different stage of the operation.

Figure 4 is a section on line 4—4 of Figure 2.

Figure 5 is a section on line 5—5 of Figure 2.

Figure 6 is a fragmentary enlargement of a portion of Figure 4.

Figure 7 is an enlarged sectional view of the primary pneumatic shown by Figure 2.

40 The same reference characters indicate the same parts in all of the figures.

Figure 1, showing in end elevation a structure embodying the automatic mechanism of my invention, also shows a portion 12 of a piano key, a sticker or abstract 13, arranged to be lifted by the key, and a hammer 14 connected as usual with the wippen 15, mounted on the sticker, these elements being adapted to be operated in the ordinary way in manual playing, the sticker resting loosely on the key, so that it may be lifted independently by a power pneumatic forming an element of the automatic mechanism hereinafter described.

55 16 represents the usual tracker-bar having a row of orifices or ports 16^a, each ar-

ranged to be closed by an imperforate portion of a note sheet 17, and opened when a perforation 17^a in the sheet registers with the port, the sheet being engaged with a 60 driven take-up spool 18, and with a supply spool 19. The tracker-bar, note sheet, and spools are supported by a frame 20. Each tracker-bar port is connected by a tube 21, with a horizontal tube rail 22, removably 65 mounted on the horizontal top board or member 23 of a casing which is suitably secured to the frame of the piano, said tube rail being detachably secured at its outer edge, as hereinafter described, to a member 25 of said casing. The tube rail 22 constitutes the base of a superstructure which is supported by said casing and includes the frame 20 and suitable standards 24 attached to the frame and the tube rail.

75 The casing, of which the member 23 forms the top, includes a vertical outer channel board 25 forming the front, and a vertical inner channel board 26 forming the back, of the casing. The said channel boards are 80 spaced apart, as shown by Figures 2, 3 and 4, and the space between these channel boards is subdivided into chambers, of which there are two, one being a vacuum chamber 29 in which a partial vacuum is maintained by 85 the suction apparatus of the instrument, operated by the usual pumping pedals, or other vacuum producing means. The other is an open chamber 30 in communication with the atmosphere. The channel boards 25 and 90 26 form the outer and inner upright walls of these chambers, the opposite ends of the chambers being formed by suitable casing members 32, which are fixed to the channel board 26, and to which the channel board 95 25 is detachably secured as by screws 60, as hereinafter described.

100 To the inner channel board 26 is fixed a horizontal valve board 28, abutting against the outer channel board and forming the bottom of a vacuum chamber 29 and the top of an open chamber 30. The bottom of said open chamber is formed by a horizontal pneumatic board 31, also abutting against the outer channel board.

105 The part 28 is called a valve board because it is provided with a vertical passage 33, and with valve seats 34 and 35, at opposite ends thereof, cooperating with the valves hereinafter described. The part 31 is called 110 a pneumatic board because to it is secured the fixed member of a primary pneumatic,

located in the open chamber 30. Said pneumatic is preferably composed of a discoidal fixed member 36, a discoidal movable member 36^a and an annular band 36^b, of membrane or thin skin secured to said members.

The vacuum chamber 29 is connected by a suitable conduit with the suction apparatus, not shown, a portion of said conduit, as here shown, being a nipple 38 fixed to 10 and extending through the inner channel board 26. The open chamber 30 communicates with the outside air through an orifice 39.

The power pneumatic shown in section 15 by Figure 2, includes a fixed member 40, secured to a fixed channeled arm, or power pneumatic rail 41, on the inner channel board 26, a movable member 40^a hingedly connected at one end to the member 40, and 20 a flexible wall portion 40^b connected with the members 40 and 40^a.

The channel 42 of the power pneumatic rail 41 communicates with a channel 43 in the inner channel board, and the last-named 25 channel communicates through a branch channel 44 with the passage 33 in the valve board. The channels 42, 43, 44, and the passage 33 collectively constitute a power conduit which is instrumental in causing the 30 operation of the power pneumatic. The tube rail 22 has a channel 45 communicating with a channel 46 in the outer channel board. A branch channel 47 in the pneumatic board 31 connects the channel 46 with passages 48 35 in the fixed member of the primary pneumatic, said member being rigidly secured to the board 31. The passages 45, 46, 47 and 48 collectively constitute a primary conduit, which is a continuation of a tracker-bar tube 21.

A vacuum chamber valve 49 cooperates with the valve seat 34, and an open chamber valve 50 cooperates with the valve seat 35, in controlling the movement of air through the 45 above-mentioned power conduit. Said valves are connected with a stem 51, which is fixed at 52 to the movable member of the primary pneumatic, and is vertically movable in a fixed guide 53 in the vacuum chamber. The area of the pneumatic member 36^a 50 is greater than that of the vacuum chamber valve 49, for a purpose hereinafter described. The vacuum chamber valve is preferably loose on the stem 51 and controlled 55 by the latter through suitable enlargement, such as a collar 51^a secured to the stem.

The vacuum chamber 29 communicates, through a contracted vent, with the primary conduit channel 46 in the outer channel 60 board, said vent being preferably provided by inserting in an orifice in the inner side of said channel board, and communicating with the channel 46, a flanged sheet metal cup 55, having an orifice 56 (Figure 6) of 65 much smaller diameter than the channel,

The operation is as follows:

When a tracker-bar port is closed by an imperforate portion of the note sheet, as shown by Figure 2, and vacuum is produced in the chamber 29, the primary pneumatic is collapsed, and the movable member thereof is drawn toward the fixed member, as shown by Figure 2; this collapse being due to the fact that the atmospheric pressure in the open chamber 30 is exerted on the exterior 75 of the primary pneumatic, and is prevented from acting on the interior thereof by the note sheet, so that the atmospheric pressure on the primary pneumatic is unbalanced. The contracted vent 56 facilitates the collapse of the primary pneumatic by permitting the withdrawal, or an induced flow of a limited quantity of air from the interior of the primary pneumatic to the vacuum chamber, as indicated by arrows *x* in Figure 80 2. The contraction of the vent 56 is such that the air passing through it to the vacuum chamber, when atmospheric pressure prevails in the primary conduit, does not appreciably affect or nullify the vacuum in 85 said chamber. The valve stem 51 is thus drawn downward and seats the vacuum chamber valve 49 and opens the open chamber valve 50, so that atmospheric pressure is admitted to the interior of the power 90 pneumatic, as shown by arrow *y* in Figure 2. The pressure of the valve 49 against its seat is determined by the difference between the area of the pneumatic member 36^a and that of the valve, the area of the member 100 36^a being in all cases greater than the area of the valve 49. I have, therefore, made provision for insuring a wind-tight closure of the valve 49 on its seat during this period of the operation, this provision being of 105 much importance, because the success of a player piano depends almost entirely on the wind-tightness of its valve system. Any leakage of air around the valves will impair the control by the operator of the dynamics of the instrument.

Under the conditions thus far described, atmospheric pressure is balanced on the inside and outside of the power pneumatic. When, however, a perforation in the note 115 sheet registers with the tracker port now being considered, air is forced by atmospheric pressure through the tube 21, and terminates the vacuum in the channel 46 and in the primary pneumatic, so that the 120 movable member 36^a is no longer held down. Atmospheric pressure entering the interior of the primary pneumatic neutralizes the pulling power of the latter, allowing the atmosphere to close the valve 50 and force 125 open the valve 49, causing an induced flow of air from the power pneumatic to the vacuum chamber 29, as indicated by arrow *z* in Figure 3, and allowing the atmospheric pressure to force the movable member 40^a of 130

the power pneumatic upward. The hammer 14 is, therefore, caused to strike a blow through the usual connections between the power pneumatic and the hammer.

5 The induced flow of air from the power pneumatic to the vacuum chamber is in the direction of the opening movement of the valve 49, and facilitates said movement.

It will be readily understood that this arrangement of the valve system materially helps to improve the touch of the pneumatic mechanism, as the motion of the valve, the travel of the air and the movement of the power or striking pneumatic all work in 10 unison and toward the same end. It is a well known fact that the tone color of a piano depends largely upon the arrangement and method of attack and by this improved system of valve mechanism, the best 15 possible results in this direction are attained.

The casing forming the chambers 29 and 30 is preferably constructed to be easily and conveniently opened to permit access to said 20 chambers, the valves, and the primary pneumatics. To this end I detachably connect the casing member formed by the outer channel board 25 to the body portion of the casing formed by the other casing members, 25 preferably by screws 60, the removal of said screws permitting the removal of the outer channel board, and as this board forms the outer or front wall of the casing, it follows 30 that its removal leaves the chambers open 35 at the front side of the body portion of the casing. To ensure air-tight joints when the outer channel board is attached, I provide packing material at 61, of any suitable compressible substance, preferably formed as 40 facing strips glued to the edges of the members of the casing body against which the outer channel board abuts. If desired, the inner side of the outer channel board may 45 be faced with packing material.

45 The tube rail 22 forms the base of a super-structure which includes the standards 24 and the frame 20, the standards being fixed to the tube rail.

To permit the removal of said superstructure and convenient access to the power pneumatics and other mechanism behind the above-described casing, I detachably secure the tube rail 22 to the top portion of said casing, preferably by screws 60^a detachably 50 connecting the upper end portion of the outer channel board 25 with the tube rail, the channel board being extended to overlap the forward edge of the tube rail. When the screws 60^a are removed, the entire super-structure may be lifted from the casing. The tube rail channels 45 register with the channels 46 of the outer channel board and the joint between the channel board and tube rail is made air-tight by packing at 61^a. 55

65 The primary pneumatic members 36 and

36^a are preferably circular disks of suitable rigid material, and the flexible member 36^b is preferably an annular strip of thin leather or membrane attached at its edges to the perimeters of said disks. To cause the flexible member to bag inward and provide suitable frictionless flexibility, I corrugate its central zone, by turning one of the discoidal members relatively to the other, until the annular member is twisted sufficiently to 70 form well defined wrinkles or corrugations 63, as indicated by Figure 7, these corrugations being practically frictionless when the pneumatic is opening and closing. This construction permits a maximum of movement 75 and a minimum of lost motion, and eliminates angles or corners in the flexible member, so that liability of cracking when corners occur is obviated.

I claim:

1. An automatic mechanism for player pianos, comprising a collapsible power pneumatic, a tracker-bar having air ports controlled by a perforated note sheet, a casing intermediate the power pneumatic and the 90 tracker-bar, subdivided to form a vacuum chamber communicating with suction apparatus, and an open chamber communicating with the atmosphere, a power conduit connecting the interior of the power pneumatic 95 with both chambers, and cooperative means whereby, when a tracker-bar port is closed, the power pneumatic is connected with the open chamber and disconnected from the vacuum chamber, and when said port is 100 opened, the power pneumatic is disconnected from the open chamber, and connected with the vacuum chamber to permit an induced flow of air from the power pneumatic to the vacuum chamber, and the collapse of the 105 power pneumatic by external atmospheric pressure, said cooperative means including a valve and valve seat for controlling the passage of air from said power conduit to the 110 vacuum chamber, the said valve seat being between the valve and the power conduit whereby said valve, to open, moves in the direction of said induced flow of air.

2. An automatic mechanism for player pianos, substantially as specified by claim 115 1, said cooperative means including also a collapsible primary pneumatic in the open chamber, having a movable member connected with the vacuum chamber valve, and of greater area than the latter, and a primary conduit communicating with said 120 tracker-bar port and with the interior of the primary pneumatic, whereby when the said port is closed, the primary pneumatic is collapsed by unbalanced atmospheric pressure, 125 and draws the vacuum chamber valve against its seat, and when the port is opened the primary pneumatic is neutralized, permitting the vacuum chamber to open and causing said induced flow.

3. An automatic mechanism for player 70 pianos, substantially as specified by claim 1, said cooperative means including also a collapsible primary pneumatic in the open 75 chamber having a movable member connected with the vacuum chamber valve, an open chamber valve connected with the primary pneumatic and with the vacuum chamber valve, and a primary conduit communicating with said tracker-bar port and with the interior of the primary pneumatic, the aforesaid conduit being connected by means of a restricted air passage to the vacuum chamber, whereby when said port is closed, 80 the primary pneumatic is collapsed by unbalanced atmospheric pressure, closes the vacuum chamber valve, and opens the open chamber valve, to permit a balanced atmospheric pressure on the power pneumatic, and 85 when the port is opened, the power of the primary pneumatic is neutralized, the vacuum chamber valve is released, and the open chamber valve is closed to allow an induced flow of air outward from the power pneumatic, permitting the latter to collapse. 90
4. An automatic mechanism for player 95 pianos, substantially as specified by claim 1, said cooperative means including also a collapsible primary pneumatic in the open chamber, having a movable member connected with the vacuum chamber valve, and of greater area than the latter, and a primary conduit communicating with said tracker-bar port and with the interior of the primary pneumatic, whereby when the said port is closed, the primary pneumatic is collapsed by unbalancing the atmospheric pressure through an induced flow of air from the primary pneumatic to the vacuum chamber, 100 and draws the vacuum chamber valve against its seat, and when the port is opened, the primary pneumatic is neutralized, and releases the vacuum chamber valve to permit said induced flow, the said primary conduit 105 being connected with the vacuum chamber by a contracted vent which permits an induced flow of air from the interior of the primary pneumatic to the vacuum chamber, sufficient to facilitate the collapse of the 110 primary pneumatic, without nullifying the vacuum in the vacuum chamber when atmospheric pressure prevails in the primary conduit. 115
5. In an automatic mechanism for player 120 pianos, a casing composed of members including a rear, power pneumatic-supporting channel board, a valve board, and a pneumatic board, both fixed to the rear channel board, a top board fixed to and projecting 125 forward from the rear channel board, and a front channel board bearing on the forward edges of the valve board, the pneumatic board and the top board, said members forming walls of a vacuum chamber 130 and an open chamber, suitable additional casing members being provided to close the ends of said chambers, the front channel board being removably attached to the casing structure formed by the other members, to expose said chambers and permit access to the contents thereof, packing means being provided for forming air-tight joints when the outer channel board is attached. 135
6. In an automatic mechanism for player 75 pianos, in combination, a casing composed of members including a rear, power-pneumatic-supporting channel board, a front channel board, a top board covering the space between said channel boards, and supplemental members forming with the above-named members a vacuum chamber and an open chamber within the casing; a superstructure comprising a frame supporting a tracker-bar and note sheet spools, a tube 85 rail forming the base of the superstructure, means connecting said frame with the tube rail and tubes extending from the tracker-bar to the tube rail, the tube rail being removably seated on the top board of the casing, and detachably secured to the casing to permit the removal of the superstructure and access to power pneumatics behind the rear channel board. 90
7. A primary pneumatic for player 95 pianos, composed of two rigid circular disks and an annular wall of flexible material, secured to and extending between said disks, and provided between the disks with corrugations formed by turning one 100 disk relatively to the other, to twist said wall, said corrugations normally contracting the central zone of the annular wall and causing the wall to bag inwardly. 105
8. In an automatic mechanism for player 110 pianos, a casing comprising an inner channel board, supporting a power pneumatic, an outer channel board spaced from the inner board, a valve board and a pneumatic board forming, with the said channel boards, 115 walls of a vacuum chamber communicating with suction apparatus, and an open chamber communicating with the atmosphere, a primary pneumatic supported by the pneumatic board, the inner channel board and valve board being provided with a power conduit communicating with said chambers, and the outer channel board being provided with a primary conduit communicating with the interior of the primary pneumatic, 120 a vacuum chamber valve, an open chamber valve, and means connecting said valves with the primary pneumatic. 125
9. In an automatic mechanism for player 130 pianos, a casing comprising an inner channel board, supporting a power pneumatic, an outer channel board spaced from the inner board, a valve board and a pneumatic board forming, with the said channel boards, 135 walls of a vacuum chamber communicating

- with suction apparatus, and of an open chamber communicating with the atmosphere, a primary pneumatic supported by the pneumatic board, the inner channel board and valve board being provided with a power conduit communicating with said chambers, and the outer channel board being provided with a primary conduit communicating with the interior of the primary pneumatic, a vacuum chamber valve, an open chamber valve, and means connecting said valves with the primary pneumatic, a contracted vent being provided connecting the primary conduit with the vacuum chamber.
10. An automatic mechanism for player pianos, substantially as specified by claim 1, said cooperative means including a vacuum chamber valve, an open chamber valve and a primary pneumatic connected with said valves, the power pneumatic, the valves and the primary pneumatic being arranged to move in the direction in which the said induced flow of air is traveling when the said port is opened, said movements opening the vacuum chamber valve.
11. In an automatic mechanism for player pianos, a casing including a valve board forming a wall of a vacuum chamber and having valve seats in said chamber, and a detachably secured front board, constituting a removable wall of said chamber; and valves in said chamber; all of said valves and valve seats being exposed for inspection when said front board is removed.
12. In an automatic mechanism for player pianos, a casing including a vacuum chamber, a valve therein, a valve outside the vacuum chamber, a circular bellows-type primary pneumatic outside the vacuum chamber, and a stem connecting the primary pneumatic with the said valves, the said primary pneumatic and valves being movable by gravity to close the valve in the vacuum chamber.
13. In an automatic mechanism for player pianos, a vacuum chamber, a power pneumatic, a power pneumatic conduit, and means for permitting the induction of a flow of air through said conduit to the vacuum chamber to cause the collapse of the power pneumatic by external atmospheric pressure, said means including a valve and valve seat for controlling the passage of air from said power pneumatic conduit to the vacuum chamber, the said valve seat being between the valve and the power pneumatic conduit whereby said valve, to open, moves in the direction of the induced flow of air.
14. A pneumatic player mechanism having a vacuum chamber, and power pneumatics and valve mechanism for effecting and controlling the striking of notes, characterized by seats for the said valves between the valves and the conduits which connect with the power pneumatics whereby the valves, to open, move in the same direction as that in which air flows when a power pneumatic operates.

In testimony whereof I have affixed my signature.

WILLIAM B. TUNSTALL.
